UNITED STATES PATENT OFFICE.

WILLIAM HOCHHAUSEN, OF NEW YORK, N. Y.

ELECTRIC-ARC LAMP.

SPECIFICATION forming part of Letters Patent No. 311,073, dated January 20, 1895.

Application filed December 13, 1883. (No model.)

To all whom it may concern:

Be it known that I, Wm. HOCHHAUSEN, a citizen of the United States, and a resident of New York, in the county of New York and State of New York, have invented certain new and useful Improvements in Electric-Arc Lamps, of which the following is a specification.

My invention relates to the general construction and arrangement of the devices for producing a separation and feed of the carbons in electric-arc lamps, and is designed more especially to provide a focusing arc lamp suitable for locomotive head-lights.

My invention consists in certain improvements in the mechanical devices supporting and actuating the carbon-carriers, and in the arrangement of magnets, motors, circuits, &c., whereby the proper movements of the carbon-carrier are secured.

The nature of my invention will be clearly understood from the subjoined description, taken in connection with the accompanying drawings, forming a part of this specification, and the novel features of the invention will be specifically stated in the claims annexed.

In the accompanying drawings, Figure 1 is an elevation of a lamp embodying my invention. Fig. 2 is a side view of the lamp. Fig. 3 is a plan of the lamp mechanism, the shafts, carbon-carriers, and other parts above the line $x x$, Fig. 1, being removed. Fig. 4 is a plan of the upper-carbon holder and the guide-plate by which it is supported. Fig. 4^a is a cross-section on the line $y y$ of Fig. 4. Fig. 5 is a plan of the lower-carbon holder and its supporting parts. Fig. 6 is a plan of a nut that engages with a revolving screw and serves to move the carbon-holder up and down. Fig. 7 is a diagram of circuits, showing the manner in which the parts are electrically connected.

H indicates the positive and H² the negative carbon of the lamp, held, respectively, in clamps or holders G G², that are constructed as shown in plan in Figs. 4 and 5, where p p² indicate the sockets or openings for the carbons. The sockets G G² are upon the ends of arms projecting from plates or supports E E², which are made to travel up and down upon guide standards or pillars F F² and M M² by means of screws B³ B⁴ and nuts attached to said supports and engaging with the screws. When the screws turn in one direction, the carbons are caused to approach, and when they

are turned in the opposite direction the carbons are caused to recede from, one another.

B B² indicate shafts or spindles, upon which or extensions of which the screws B³ B⁴ are formed. Shaft B forms an extension of the armature for an electric motor or the shaft of any other prime mover, by which said shaft may be made to turn in either direction. Attached to said shaft is a wheel or pinion, C, gearing with a second wheel or pinion, C², of half the circumference, upon shaft B², so that the nut upon screw B⁴, which nut imparts movement to the positive carbon, may be made to move twice or approximately twice as fast as the nut upon screw B³, which imparts movement to the negative carbon. The wheels or pinions are insulated from the shafts by sleeves or bushings of insulating material.

The construction and method of operating the electric motor will be described further.

The mounting and arrangement of the parts so far described are in detail as follows:

The pillars F F² are of brass or other suitable material, preferably a conducting material, and are mounted directly in a conducting-plate, P⁷, which is in turn secured upon standards or frames S⁵, supported on a base-plate, A⁷. Plate P⁷ is preferably insulated from standards S⁵, although this is not essential, and the pillars F F² screw into said plate, or are otherwise secured to the same. The plate P⁷, and therefore the pillars F F², are put in electrical connection with the positive side of the main line by means of a binding-post, h, mounted on said plate, or by any other means. Shaft B² is journaled at one end at b¹ in a cross-piece uniting the pillars F F², and at the other end in a cup, b³, upon plate P⁷. The pillars M M², which are put in connection with the negative side of the lamp by any suitable means, are mounted on a plate, P⁸, insulated from the plate P⁷, as indicated. Secured to the top of the latter pillars, but insulated therefrom, is a plate, F⁸, provided with openings, in which pillars F F² fit snugly, so that all the pillars are united and braced by one another. The upper end of the shaft B, which imparts movement to the negative carbon-holder, has a bearing at its upper end in a plate, b², secured to the under side of plate F⁸, and insulated therefrom, so as to be out of electrical connection with the pillars F F². The lower end of the shaft B is seated at b on the base-plate A⁷. The plate F⁸, besides staying the pillars and

forming a support for the upper end of shaft B, also forms a guide for the elongated pins E³ E⁴, projecting, respectively, from the plates E E², and extending through openings in F³, said openings being provided with insulating-bushings, or the pins themselves being of insulating material, so as to prevent the plate F³ from electrically connecting the plates or supports E E². The pins E³ E⁴ serve to steady the plates E E² as they slide on the pillars, and thus prevent them from binding.

At D D² are indicated nuts connected with or mounted upon the plates or supports E E², and arranged to engage, respectively, with the screws B³ B⁴, in such way that when shaft B turns in one direction the supports E E² will approach, and when the shaft B turns in the other direction they will recede.

The nuts are made, as shown in Fig. 6, so that they may be disengaged from the screws at pleasure to permit the plates E E² to be quickly returned to their extreme positions when new carbons are placed in their sockets. Each nut is made in two parts, D³ D⁴, united on a pin, f, attached to the plate E or E². One part, D⁴, carries a pivoted or swinging piece, D⁵, provided with a clamping-screw adapted to bear against the end of D³ when the two parts are brought together.

To disengage the nut from the screw-shaft, the binding-screw is loosened and the piece D⁵ swung outward, whereupon the two parts D³ D⁴ may be opened by turning on their pin f. The spring D⁶ serves to hold the piece D⁵ in position with the part D³, locked by the binding-screws, as shown in Fig. 4.

The arms which carry the holders G G² are made adjustable, so as to permit the carbons to be brought into line or to be set out of line, as may be desired. For this purpose the plate g², to which the arm is united, is provided with slots, through which pass the clamping-screws g³. The plates g² slide on the plates E or E², or extensions from the latter, and the clamping-screws screw into the latter plates and hold the parts together, as indicated in Fig. 4^a.

A indicates the armature for an electric motor of any desired kind. This armature is mounted in any ordinary or suitable manner upon the shaft B, so as to turn the same when the armature rotates. The armature may be wound after the manner of the armature of a Gramme dynamo-electric machine or motor.

A⁴ indicates one of the commutator-brushes of the motor, and A⁹, Fig. 7, the other commutator-brush. These brushes are both indicated in Fig. 7 as bearing on the commutator-cylinder enlarged.

A⁵ A⁶ indicate the curved pole-pieces between which the armature rotates. These pole-pieces form extensions of the cores of electro-magnets A² A³, which magnets are preferably united by a cross-piece, A¹⁰, of any suitable material, to brace the parts. The cross-piece may be of magnetic material, in which case the pole-pieces form the poles of a horseshoe-magnet having a coil upon each of

its legs. The magnets are supported by securing the pole-pieces to the cross-bar of a frame, the standards of which are indicated 70 at K⁴.

The direction of rotation of the motor is governed by causing the current to flow in one direction or the other through the armature, according as the carbons are to be 75 brought together or to be separated. This may be accomplished by the means to be presently described, or by any other suitable devices.

Upon the armature-shaft is a brake-wheel 80 consisting of a disk, a, having projecting pins, with which a pin upon the end of an arm, a², is made to engage whenever the current ceases to flow through the motor-armature. The arm a² extends from the rock-shaft of an armature acted upon by an electro-magnet, a³, mounted on the pole-piece A⁵. The rock-shaft for the armature is mounted on brackets secured, as indicated, to a non-magnetic plate uniting the pole-pieces A⁵ A⁶, and to the 85 under side of the frame to which the pole-pieces are secured. So long as the magnet a³ is energized it attracts the armature and holds the brake-pin out of engagement with the brake disk or wheel against the action of the 90 spring a⁵, Fig. 3. When the attraction of the magnet diminishes or ceases, the spring a⁵ immediately brings the parts of the brake into engagement and stops the rotation of the armature-shaft, thus preventing movement of the 100 latter after the current ceases to flow in the motor-armature.

The desired operation of the motor and of the brake is controlled by an electro-magnet, O, in a derived circuit of high resistance 105 around the arc, acting upon an armature, M¹², pivoted in brackets extending from a plate, L², of insulating material, that rests upon the base-plate A¹. Armature M¹² is provided with a downwardly-extending circuit-closing arm, 110 M⁵, which works against a double-contact lever, N, which is also mounted in brackets extending from plate L², and has two insulated contact-points, m n, one of which is placed in electrical connection with commutator-brush 115 A⁹, while the other is connected by wire 9 with the other commutator-brush, A⁴. A retractor acting upon N against the pull of magnet O is indicated at i. This retractor may be adjusted by means of a turning-pin, h². The 120 branch wire 6 includes the coils of the motor-magnet A³; the branch wire 9 includes the coils of motor-magnet A². The branches 6 9 unite at t in a wire, 5, which forms one pole of a circuit, in which the circuit-closing arm M⁵ is 125 the other pole. As will be seen, the armature of the motor is in a bridge-wire uniting the two brauches 6 9, so that a proper excess of current or potential in one branch over that in the other will cause current to flow in a 130 determinate direction through the armature, and in an amount dependent upon the resistance of coils A² or A³, which, as arranged, act as diverting-coils. If, for instance, the cur-

rent in the portion of branch 6 connected to m be greater than in 9 and n , or if current flow in 6 while no current is flowing in 9, the current will divide at f^9 , and one portion will 5 pass from f^9 through the motor-armature to f^{10} , and thence through A^2 to t . The other portion will pass from f^9 through A^3 to t , and the motor will turn in a certain direction, which in the present arrangement is a direction 10 to cause the carbons to approach. If the potential on 9 be the greater, the current will divide at f^{10} , and one portion will pass through the motor-armature in a reverse direction to f^9 and through coils of A^3 to a point, t . The other portion will pass through A^2 to the point 15 t , and the motor will turn in the opposite direction, so as to cause the carbon points to recede. If the current in both branches 6 9 be the same, no current will pass in the bridge 20 from f^{10} to f^9 , or in the opposite direction, and the motor-armature will come to rest. The magnet a^3 , controlling the brake, is also in this bridge-wire, so that the brake will be applied while this condition obtains. While the arm 25 M^5 is bearing with equal pressure against both points m n the flow of current in both branches is the same, and there will be no movement of the electric motor. If, however, the attraction of magnet O increases, the pressure on m will 30 diminish, and if the attraction of O be strong enough the contact with m will be broken. The contact with n will, however, be preserved, with the result of causing more current to flow in 9 than in 6. If the attraction of O diminish 35 so far as to permit the retractor of N to act and break or lessen the contact at n , while preserving the contact at m , there will be a greater potential in 6 than in 9 at the points f^9 f^{10} , where the bridge-wire is connected, and current will therefore flow through said bridge-wire from the branch having high potential to the branch having lower potential, and in 40 a direction to cause the motor to revolve in a certain direction. The differences of potential thus produced may be, as is obvious, due 45 simply to differences of pressure, and consequent resistance at the points m n , or they may be due to the absolute breaking of contact at one point while contact is preserved at 50 the other. The retractor i is so adjusted that with an arc of normal length there is a balance between its pull and the pull of magnet O , so that the circuit-closing arm M^5 will bear 55 against both contacts m n , and there will be no tendency for the current to flow in either direction through the bridge-wire containing the motor-armature.

In connection with the armature M^2 and the circuit-closing devices, I employ an auxiliary device that serves, when the lamp is 60 out of action, to hold the lever N in such position that contact will be made with point n and broken with m , so that if the carbons are out of contact at starting the motor will 65 immediately begin to rotate in a direction to bring the carbons together. This device consists of lever L , pivoted at f^5 , and having a

stud, g , that is made to bear on the armature M^2 , and thus hold the armature in the position shown in Fig. 7, by means of the retractor d , for an armature-lever, K , which latter is pivoted on a post, I^2 , and is connected with lever L by a link, e . (See Figs. 1 and 2.)

I indicates an electro-magnet of low resistance, that acts upon the armature when the 75 circuit is established through the carbons, and pulls the lever L away from the armature M . The positive binding-post h forms a back contact-stop for the armature-lever K .

The various parts hereinbefore described 80 are connected by the usual devices of binding posts or clamps and connecting-wires, after the manner shown in the diagram Fig. 7. Entering at binding-post h , there are two 85 paths provided for the main circuit, one through carbons H H^2 when they are in contact or the arc is formed through the coils of magnet I , to a point, 25, the other from h , through armature K when the electro-magnet I is not energized, artificial resistance R^5 , 90 to point 25. Resistance R^5 is made sufficient to insure the energization of magnet I when the carbons come together. From 25 connection is made to circuit-closing arm M^5 , from which point there are two paths for 95 the current, one or both of which are closed, according to the position of the arm M^5 , as before explained. The one path is through n 9 to f^{10} , where the current divides through A^2 on the one side and a^3 , A^4 , A , A^9 , and A^3 on 100 the other, reuniting at t , from which point a connection is made to the main line on the negative side of the lamp. The other path is through m 6 to f^9 , where the current splits, 105 passing on the one side through A^3 and on the other through A^9 A A^4 a^3 f^{10} A^2 and to t , as before. The electro-magnet O is in a derived circuit of high resistance around the arc, as usual, which circuit is indicated by the line marked 7.

The general operation is as follows: Let it be supposed that there is no current on the main line and that the carbons H H^2 are out of contact. Lever L is then forced against M by retractor d and armature K , and the latter is 110 against its stop h . The circuit through the lamp is then as follows: From h through K I^2 R^5 M^5 n 9 f^{10} , thence either through a^3 A^4 A^9 A^3 6 t and out, or through A^2 direct to t and out. When the current is turned on, none 115 passes through the carbons and magnet I , because the carbons are out of contact, and therefore lever L maintains its position so as to hold the arm M^5 in contact with point n only. The current then passes in the course just 120 detailed, and in a direction through the bridge-wire and armature, to cause the shaft A to rotate, so as to raise the lower plate, E , and lower carbon, the magnet a^3 acting at the instant the current flows to withdraw the brake 125 or stop from engagement with the brake-wheel a . The movement of shaft A imparts through wheels C C^2 a reverse movement to shaft B^2 , and the upper plate and carbon are simulta-

neously lowered. The movement of the motor in this direction continues until the carbons come into contact, whereupon the magnet I is energized and draws down the armature K against the force of its retractor d, and holds it in this position so long as current flows through the carbons. The connection through the resistance R⁷ is thus broken, and the lever L is also operated so as to relieve 10 the armature M from the pressure of said lever, and as there is now but little current flowing in the magnet O, owing to the comparatively-small resistance of the circuit through the carbons, &c., the retractor i acts on N and 15 swings the same, so that it rocks on contact-arm M⁵, and for an instant forms the connection between M⁵ and both points m n, followed instantly by a breaking of the contact with n, the contact with m being preserved. The 20 effect of making contact with both points m n is, as before explained, to cause a cessation of current in the bridge-wire, and therefore a stoppage of the motor and application of the brake. When the contact with n is broken, 25 the current flows in the other direction through the bridge-wire, and simultaneously with the withdrawal of the brake-lever a² the motor begins to revolve in the other direction, so as to cause a reverse movement of the two shafts 30 B B² and a consequent movement of the two plates or supports E E² in a direction to separate the carbons and form the arc. This movement of the motor continues until the separation reaches the normal or adjusted 35 amount, at which time sufficient current is forced into the derived circuit to energize the magnet O, so that it may move the arm M⁵ against the influence of the retractor i, and cause contact to be made with both points 40 m n. The motor is thus brought to rest, as before explained. The magnet O holds the arm M⁵ in this position so long as the arc is of the adjusted length; but when by consumption of the carbons the arc lengthens 45 the magnet O acquires more power and gradually pulls the arm M⁵ over until contact is broken or lessened with m, so that the motor will rotate in a direction to feed the carbons toward one another. The movement in this 50 direction continues until the arc is reduced to its normal length, when the balance between the pull of magnet O and the retractor i is established, and the arm M⁵ makes connection with both contacts, so that the motor comes 55 to rest and remains at rest until the balance is again disturbed.

Modifications will readily suggest themselves to those skilled in the art.

I do not limit myself to the running of the 60 motor by the lighting-current, as it is obvious that the motor might be operated by a current from any source, the connections being controlled, as herein described, by the circuit-closing devices operating in accordance with 65 the condition of the circuit between the carbons.

Other forms of motor might also be em-

ployed for imparting the desired movement to the shafts B B².

I am aware that it is not new to adjust the 70 position of a carbon in an electric lamp by means of an electric motor and a screw-shaft, and to automatically determine the direction of movement of the carbon by determining the direction of flow of current in the motor. 75 I do not therefore wish to be understood as claiming such a combination, broadly.

What I claim as my invention is—

1. The combination, substantially as described, of the two screw-shafts, each carrying a nut for supporting or actuating a carbon, an electric-motor armature carried by one of said shafts, and two wheels gearing with one another, the wheel on one shaft having twice the circumference of that upon the other. 80

2. The combination of the shafts B B², the two pairs of standards, each having a cross-piece for the support of a shaft, and the guide-plates E E², each carrying a nut and a carbon-holder. 85

3. The combination of the two pairs of standards, the cross-pieces F³ b⁴, the shafts B B², pinions C C², and the electric motor having an armature mounted on one of the shafts B B². 90

4. The combination of the pillars F F² M M², the insulated uniting-plate F³, the sliding plates E E², for carrying the carbons, and the guide-pins E³ E⁴, as and for the purpose described. 95

5. The combination of the two pairs of pillars, the uniting-plate F³, the two screw-shafts, one of which is stepped in a cross-piece for one pair of pillars, the other in the plate F³, the supporting-plates for the carbon-carriers, 105 carrying nuts that engage with the screw-shafts, and the guide-pins E³ E⁴, passing through the plate F³, as and for the purpose described.

6. The combination, substantially as described, of the two shafts B B², connected, respectively, with the positive and negative carbons, and the wheels or pinions upon said shafts gearing with one another, and one or both separated from the shafts by sleeves of insulating material. 110

7. The combination, with the screw-shaft, of a support for the carbon, and the nut constructed in two portions swinging on a pin, and having upon one portion a pivoted clamping or connecting piece, D⁵, as and for the purpose described. 115

8. In an electric lamp, the combination of two guiding pillars or standards forming a portion of the circuit, a sliding plate or cross-piece sliding on said standards, and a horizontally-adjustable carbon-holder supported on said plate, as and for the purpose described. 125

9. The combination of the two sliding plates or supports E E², the two carbon-holders supported thereby, and the horizontally-adjustable arms carrying the holders and sliding in and out upon the plates. 130

10. The combination of the plate E or E²,

the two pillars F F' or M M', the horizontally-projecting adjustable arm carrying the holder, the screw-shaft passing through the plate, and the nut supported by the plate and made 5 in two parts pivoted on a pin projecting from said plate.

11. The combination, in an electric lamp, of the screw-shaft B, carrying a nut for moving the carbon up or down, an electric motor 10 whose armature is supported on said shaft, and a magnet in a high-resistance branch around the carbons, for reversing the direction of the current in said armature, according to the condition of the circuit between the carbons.

12. The combination of the screw-shaft, the nut upon said shaft for imparting movement to the holder, the electric-motor armature in a bridge between two branch wires, and a double-contact circuit-closer for admitting 20 current to one or both branches, in accordance with the condition of the carbon circuit.

13. The combination, with the carbon-carrier in an electric-arc lamp, of an electric motor for imparting movement thereto, having its armature placed in a bridge-wire between two branches, a double-contact circuit-closer, whereby the circuit of either or both branches may be closed, and an electro-magnet in a derived circuit around the carbons 25 for controlling said circuit-closer, as and for the purpose described.

14. The combination, with mechanism in an electric lamp for imparting the desired feeding and separating movement to the carbon-carrier, of an electric motor actuating said mechanism, a bibranch circuit, a brake-controlling electro-magnet in a bridge-wire between said branches, and a double-contact circuit-closer for closing the circuit of one 40 branch, or of both together, as and for the purpose described.

15. The combination, with the feeding and separating mechanism for an electric lamp, of an actuating electric motor, a bibranch circuit, each branch of which contains the coils of one of the field-magnets for the motor, a bridge-wire containing the armature for the motor, and means for varying the potential of the current in the two branches, as and for the 45 purpose described.

16. The combination, with feeding and separating mechanism for a carbon of an electric lamp, of an actuating electric motor, a bibranch circuit, each branch of which contains one of the motor field-magnet coils, a bridge-wire containing the armature of the motor, a brake electro-magnet in said bridge-wire, which permits a brake to be applied to the motor when the current in the bridge-wire 55 ceases or weakens, and means for admitting current to both branches while the arc is of normal length, and of causing a decrease in one branch or the other, according as the resistance between the carbons is above or below 60 normal, as and for the purpose set forth.

17. The combination of the carbon separating and feeding mechanism, an electric motor for actuating said mechanism, circuit-controlling devices whereby the feeding and separating movement of the motor is controlled, 70 mechanism tending, when no current is passing through the carbons, to hold the circuit-controlling devices in position to cause the motor to feed the carbons, and an electro-magnet in the carbon circuit for disengaging and holding 75 said mechanism out of action, for the purpose described.

18. The combination, in an electric lamp, of an electric motor for feeding or separating the carbons, a circuit-controller for determining 80 the movements of the motor, a derived-circuit electro-magnet acting on the circuit-controller, devices for holding the circuit-controller in position to cause a feed of the carbon or carbons when no current is flowing through the 85 carbons, and an electro-magnet energized when the carbons come together for withdrawing and holding said devices away from the circuit-controller, whereby the retractor of the latter may be permitted to act and throw the 90 circuit-controller into position to cause a separation of the carbons.

19. The combination, with the electric motor by which the carbons are caused to approach or recede from one another, of the circuit-controlling lever, the derived-circuit magnet O, a lever, L, adapted to bear on the circuit-controlling lever, an armature, K, connected with said lever L, and a magnet, I, in circuit with the carbons, as and for the purpose 95 described.

20. The combination of the magnet I in circuit with the carbons, the armature K, normally closing a circuit independent of the carbons and magnet I, an electric motor for 100 governing the position of the carbons, a circuit-controller and derived-circuit magnet, and intermediate devices between the circuit-controller and the armature K, whereby the retractor for the latter may hold the circuit-controller in position to cause the motor to force the carbons together when no current is 105 passing between them.

21. The combination, with the actuating mechanism for an electric-arc lamp, of an 110 electric motor, a bibranch circuit, each branch containing a resistance, a bridge-wire connecting said branches and containing the motor, and means for admitting current to one branch or the other, according to the distance 115 between the electrodes of the lamp, whereby the motor may be caused to move in proper direction to lengthen or shorten the arc.

Signed at New York, in the county of New York and State of New York, this 26th day 120 of September, A. D. 1883.
